Primary Examiner — David Muller(74) *Attorney, Agent, or Firm* — Gearhart Law LLC(57) **CLAIM**

The ornamental design for a syringe, as shown and described.

DESCRIPTION

FIG. 1 is a perspective view of the syringe;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an exploded parts view of FIG. 1 showing the barrel and the plunger of the syringe. The plunger, as shown, is symmetrical such that all other views of the plunger not explicitly shown in the drawings are identical to that shown in FIG. 8.

The dash-dot lines shown in FIG. 8 are used to illustrate the relationship between the barrel and plunger of the syringe and form no part of the claimed design.
